DESIGN FOR A COMBINATION FAN AND SMOKING TABLE

William L. Kisling, St. Louis, Mo.

Application November 17, 1938, Serial No. 81,164

Term of patent 7 years

To all whom it may concern:

Be it known that I, William L. Kisling, a citizen of the United States, residing at St. Louis, in the State of Missouri, have invented a new, original, and ornamental Design for a Combination Fan and Smoking Table, of which the following is a specification, reference being had to the accompanying drawing, forming part thereof.

Figure 1 is a top plan view of a combination fan and smoking table, showing my new design.

Figure 2 is a side elevational view.

Figure 3 is a vertical diametrical section through the upper portion of the fan and smoking table.

The dominant features of my design are shown in solid black lines. The pedestal portion, shown in Fig. 2, appears the same on the hidden side.

I claim:

The ornamental design for a combination fan and smoking table, as shown and described.

WILLIAM L. KISLING.
